UNITED STATES PATENT OFFICE.

PAUL J. NEITZEL, OF SOUTH BEND, INDIANA.

DESIGN FOR A GAME-BOARD.

SPECIFICATION forming part of Design No. 32,632, dated May 1, 1900.

Application filed April 2, 1900. Serial No. 11,267. Term of patent 7 years.

To all whom it may concern:

Be it known that I, PAUL J. NEITZEL, a citizen of the United States, residing at South Bend, in the county of St. Joseph and State 5 of Indiana, have invented and produced a new and original Design for a Game-Board; and I do hereby declare the following to be a full, clear, and exact description of the same, reference being had to the accompanying 10 drawing, forming a part thereof.

My invention relates to designs for game-boards; and it consists in the configuration of parts, which will be more fully described hereinafter.

5 The accompanying drawing represents a perspective of a game-board embodying my invention.

A represents the board proper, which is rectangular in shape and provided with the 20 flanges B around its outer edges. Extending inwardly toward the center of the board from each one of its four sides are the triangular-shaped projections or portions C, which have their upper surfaces flush with the top of the 25 flange B, and which projections or portions have their two inner edges made rounding, while their outer edges are straight, so as to correspond with the flanges B, against which they bear. Extending across each one of the 30 corners D is a curved partition E, which is also about the same height as the flanges B, and which partitions form one side of the chambers F, one of which is formed at each corner of the board. Opposite each corner 35 and also rising to the height of the partitions B is the curved guide G, which has its outer ends to project inwardly toward the center of the board about on a line with the inner points H of the projections C, and these curved 40 guides, in connection with the projections C, the curved partitions E, and the flanges B, form the curved grooves or runways I, as shown.

At the center of the board there is outlined

by the two parallel lines J a rectangular figure K, which is arranged so that its corners point toward the corners of the board, as shown. This rectangular figure K is divided by the two cross-lines L into four divisions and form at the inner corner of each one of these 50 divisions an oval figure or outline M, their inner points centering at the center of the two division-lines. These four oval figures M are inclosed in the rectangular figure N, and inside of this rectangular figure N is outlined 55 another rectangular figure O, the sides of which are parallel with the rectangular figures N and K. The spaces between the two parallel lines J which form the outlines of the figure K are divided by cross-lines, as shown. 60

At each of the corners of the rectangular figure K is outlined a figure P P', corresponding in shape to a clover-leaf, two of them, P, being much broader than the corresponding ones, P'. These clover-leaf-shaped figures P project into 65 the semicircular-shaped fields Q, formed by the curved guides G. Upon each of the narrower figures P' are formed three circles, and outside of the figure, where the three parts of the figure are joined together, are two other 70 circles, as shown. Upon each of the figures P there are four small circles as compared with the three upon the narrower ones, and these two figures have also small circles placed outside of them, as shown. Also at each corner 75 of the rectangular figure K is a small circle, as shown.

Having thus described my invention, I claim—

The design for a game-board, substantially 80 as shown and described.

In testimony whereof I affix my signature in presence of two witnesses.

PAUL J. NEITZEL.
